UNITED STATES PATENT OFFICE.

PERCY G. PARIS, OF BETHLEHEM, PENNSYLVANIA, ASSIGNOR TO BETHLEHEM STEEL COMPANY, OF SOUTH BETHLEHEM, PENNSYLVANIA, A CORPORATION OF PENNSYLVANIA.

METHOD OF AND APPARATUS FOR CASTING CHARGES FOR PROJECTILES.

1,282,623.

Specification of Letters Patent. Patented Oct. 22, 1918.

Application filed January 2, 1915. Serial No. 310.

To all whom it may concern:

Be it known that I, PERCY G. PARIS, a subject of the King of Great Britain, and resident of Bethlehem, Northampton county, 5 State of Pennsylvania, have invented certain new and useful Improvements in Methods of and Apparatus for Casting Charges for Projectiles, of which the following is a specification.

10 This invention relates to the method and apparatus for casting explosive charges for projectiles.

In the apparatus heretofore employed for this purpose, trouble has been experienced 15 on account of air bubbles remaining in the charges and thus seriously affecting the quality of the product. It is the object of the present invention to overcome this disadvantage and to provide a method and apparatus which may be conveniently employed and which produces the minimum amount of waste, by eliminating the use of pouring devices. It is also the object of the 20 invention to provide a method and apparatus which will produce a dense charge that will not be subject to the usual defects arising from shrinkage, in the methods heretofore employed.

The novel features of the invention will 25 be apparent from the following description taken in connection with the accompanying drawing which is a vertical section of an apparatus embodying my invention.

Referring to the drawing, 10 indicates the 30 body of a mold in which the charge is formed. The body 10 has a removable bottom 11 which is secured by bolts 12 or any other suitable fastening devices. The upper end of the body 10 is provided with a flange 35 13 and has secured thereon a riser 14 provided with a jacket 15 through which a heating medium may be circulated, connections 16 and 17 being provided for this purpose. The jacket 15 has a flange 18 which is secured 40 to the flange 13 by bolts 19 or other suitable means. The upper end of the riser 14 is provided with a cap 20 in which a pipe 21 is secured, this pipe communicating 45 with the interior of the riser 14. A three-way valve 22, having an operating handle 23, is connected with the pipe 21 and also with a suction pipe 24. The pipe 24 leads 50 to any suitable form of exhauster (not

shown) for the purpose of exhausting the air from the mold 10 and the riser 14. The 55 branch 25 of the valve 22 communicates with the external atmosphere so that the interior of the riser 14 may be placed in communication with the external atmosphere when desired.

A pipe 26 extends through the jacket 15 and is secured to the riser 14 adjacent the lower end thereof. This pipe extends into a reservoir 27, to a point near the bottom thereof, and has a valve 28, controlled by 60 a handle 29, by means of which the flow of the charge-forming material through the pipe 26 may be controlled. The reservoir 27 is provided with a jacket 30 through which a heating medium may be circulated, 65 inlet and outlet pipes 31 being provided for this purpose. It will be observed that, in the arrangement illustrated, the pipe 26 extends over the upper edge of the reservoir 70 27 and, in order to prevent the fluid in this pipe from solidifying, a suitable jacket or steam coil 32 is arranged on the exposed portion of the pipe.

In the operation of the apparatus a suitable supply of molten charge-forming material is maintained in the reservoir 27 and when it is desired to cast a charge the valve 80 28 is closed and the valve 22 is turned so as to establish communication between the pipe 24 and the interior of the riser 14 and thus 85 exhaust the air from the interior of the riser and the body 10. When the air is exhausted from the mold, valve 22 is closed so as to cut off pipe 24, the valve 28 is 90 opened and the charge-forming material is allowed to siphon over into the mold so as to fill the body 10 and also the riser. When the riser 14 is approximately full valve 28 is closed and the charge-forming material 95 allowed to remain there during solidification. It will be understood that the riser 14 is heated by steam or other heating medium in the jacket 15 when the apparatus is in use so that the material in the riser will be maintained in a fluid condition while 100 the material in the body 10 is solidifying, and as the solidification in the body 10 proceeds, any tendency of the charge to shrink will be overcome by material from the riser and in this way the charge, when completely solidified, will fill the mold 10. If

desired a suitable protecting casing of paper or other material may be placed in the mold 10 before the charge is cast.

After the charge has solidified the valve 5 28 is opened and the valve 22 turned so as to admit air to the riser 14. In this way the material in the riser will be drained back through the pipe 26 into the reservoir 27. The body 10 of the mold may then be 10 detached from the jacket 15 of the riser and the charge extracted from the mold by removing the bottom 11 of the mold. The charge will have a solid or semi-solid projection on the upper end thereof and when 15 this is removed the charge is in the completed form. The body 10 is then attached to the jacket 15 and the bottom 11 placed in position and the operation of casting repeated. It will be understood that several 20 different molds may be arranged about the reservoir 27 and the operation of casting the charges may proceed in all of the molds simultaneously. It will also be evident that the elimination of pouring devices avoids 25 the usual loss due to the material solidifying on these devices and necessitating its being scraped therefrom. The maintenance of the riser in a fluid state not only insures against shrinkage of the casting but also 30 permits the material in the riser to be readily drained back into the supply reservoir 27. The exhaustion of the air from the mold before the casting operation insures that there will be no air bubbles in the 35 charge or on the surface thereof.

Having thus described the invention what is claimed is:

1. The method of making charges which consists in exhausting the air from a hermetically sealed mold, having a riser thereon, siphoning the charge-forming material from a molten supply thereof into the mold and riser, maintaining the material in the riser in a molten state while the charge is 40 solidifying and thereafter expelling the molten material from the riser to the supply. 45

2. The method of making charges which consists in exhausting the air from a hermetically sealed mold, having a riser thereon, siphoning the charge-forming material from a molten supply thereof into the mold and riser, and maintaining the material in the riser in a molten state while the charge 50 is solidifying, and admitting air to the mold and draining off the material in the riser while it is in a fluid state.

3. In apparatus of the class described, the combination of a hermetically sealed 55 mold having a riser, a suction pipe connected with said riser for the purpose of exhausting air from the mold, means for maintaining a supply of molten charge-forming material, means for conveying said 60 material from said supply to the mold at

a point adjacent the bottom of the riser, without admitting air to the mold, a valve in the last-mentioned means, means for admitting air to the riser, and means whereby the mold may be opened to permit removal 70 of the charge.

4. In apparatus of the class described, the combination of a hermetically sealed mold having a riser, a suction pipe connected with said riser for the purpose of 75 exhausting air from the mold, means for maintaining a supply of molten charge-forming material, heated means for conveying said material from said supply to the mold at a point adjacent the bottom of the riser, without admitting air to the mold, a valve in the last mentioned means, means whereby the riser may be heated to maintain the material therein in a fluid condition, means for admitting air to the riser, and means 80 whereby the mold may be opened to permit removal of the charge.

5. In apparatus of the class described, the combination of a mold having a riser thereon, a supply reservoir arranged to be 90 heated for the purpose of rendering the charge-forming material fluid, a pipe leading from the lower part of said reservoir to said mold adjacent the bottom of said riser, a suction pipe connected with said riser, 95 and means permitting a separation of the mold at the bottom of the riser.

6. In apparatus of the class described, the combination of a mold comprising an upright body portion, a removable bottom 100 on the body portion and a jacketed riser secured to the upper end of the body portion, a reservoir arranged to be heated for the purpose of rendering the charge-forming material fluid, an externally heated pipe 105 for the purpose of conducting the charge-forming material from the lower part of said reservoir to said riser adjacent the lower end thereof, a valve in said pipe, and a suction pipe, connected with the upper 110 end of said riser.

7. In an apparatus of the class described, the combination of a mold comprising an upright body portion, a removable bottom 115 for said body portion, a jacketed riser detachably secured to the upper end of the body portion, a reservoir, for the charge-forming material, arranged to be heated, a heated pipe for conducting the charge-forming material from the lower part of 120 said reservoir to said riser adjacent the lower end of the latter, a valve in said pipe within said reservoir, a suction pipe connected with the upper end of said riser, and means whereby communication may be 125 established between the interior of the riser and the external atmosphere.

8. In an apparatus of the class described, the combination of a mold comprising a 130 body portion, a removable bottom for said

body portion, a jacketed riser to which said body portion is detachably secured, a reservoir provided with means whereby the charge-forming material therein may be heated, a heated conduit for conveying the charge-forming material from the said reservoir to the mold, a suction pipe and a three-way valve connected with said pipe and said riser and adapted to establish com-

munication between the riser and the suction pipe or the riser and the external atmosphere. 10

In testimony whereof I affix my signature in presence of two witnesses.
